UNITED STATES PATENT OFFICE.

DUNCAN HALSTEAD, OF CHEBOYGAN, MICHIGAN.

NON-BINDING SLEIGH-BUNKER.

SPECIFICATION forming part of Letters Patent No. 794,861, dated July 18, 1905.

Application filed August 13, 1904. Serial No. 220,643.

To all whom it may concern:

Be it known that I, DUNCAN HALSTEAD, a citizen of the United States, residing at Cheboygan, in the county of Cheboygan and State 5 of Michigan, have invented a new and useful Non-Binding Sleigh-Bunker, of which the following is a specification.

My invention relates to improvements in sleighs; and the objects of my improvements 10 are, first, to provide a sleigh wherein the runners will turn under the beam, and thereby prevent the bunker from binding under any circumstances, whether the load thereon is evenly distributed or not, and of such nature 15 that it may be attached to any sleigh now manufactured; second, to provide a sleigh that will start easily, and, third, a sleigh that will steer more easily. I attain these objects by the mechanism illustrated in the accompanying drawings, in which—

Figure 1 is a top view of the entire sleigh, showing the entire mechanism in operative position therein; Fig. 2, a longitudinal section view of the sleigh, and Fig. 3 represents 20 a cross-section of the front sleigh.

Similar letters refer to similar parts throughout the several views.

A metal knuckle D fits over the top of each of the runners R and is fastened thereon by 25 two bolts. To the upper side of D and to its center is permanently attached the swivel-pin L, which runs through a corresponding hole in a metal plate C, which is bolted on the lower side of the wooden beam N. This provides a swivel whereby the runners will turn 30 under the beams. M is the bunker upon which the load rests and instead of being rocked on the under side, as at present, can be made straight, so that it will bear upon the 35 whole length of the beam N. This bunker is attached to the beam by a king-bolt K, running through the center, and E is a bunker-lock, consisting of an iron bolt running into the beam N, with the upper part projecting 40 to hold the bunker M stationary when loaded, one of such bunker-locks being placed on either side of the king-bolt K. These locks are so made that they can be pulled out of 45 their sockets in the beam, so as to allow the

bunker to swing horizontal with the sleigh 50 when empty, if so desired.

B is a sheave attached to the upper part of the beam N in the front sleighs only, there being two of such sheaves, one on either end of the beam.

F is a purchase-tongue attached to and running from the roll P of the front sleigh to the center of the front of the beam N and is attached thereto by a clevis H. To the front of the purchase-tongue is mortised and attached 60 the main tongue S. Near the center of the purchase-tongue is bolted a link O, to which is attached two chains A, one running through the right sheave and attached to the left eyebolt J on the hind runner and the other running through the left sheave and attached to the right eyebolt J in the hind runner, so that by turning the main tongue either one way or the other it not only starts the front 65 runners, but also the hind ones at the same time, (see the dotted lines,) the runners turning on the swivels attached to them, as heretofore described.

T is a stay chain or cable running from each of the eyebolts of the front runner to a 70 link O near the center of the purchase-tongue F. These stay-chains are only used when the sleighs are empty and it is desired to turn the bunker in a horizontal position. The chains will then keep the runners and beams in a 75 stationary position.

In practice modifications of the specific construction shown may be made and any suitable materials and proportions may be used for the various parts without departing 80 from the spirit of the invention.

Link-bars G are loosely connected at their ends to the ends of the bolsters M to insure a united movement of the bolsters.

What I claim as my invention, and desire to 90 secure by Letters Patent, is—

A device of the character described, comprising front and rear sleds, each consisting of a pair of runners R, link-bars P loosely connecting their forward ends, knuckles D, 95 pivot-pins L, main bolsters N, sand-bolsters M pivoted upon the bolsters N, link-bars G loosely connecting the ends of the bolsters M,

means for locking the bolsters M and N together, the pivoted draft-tongue S, the purchase-tongue F having its rear end loosely connected to the front bolster N and its forward end bifurcated to engage the tongue S and the front link-bar P, pulleys B upon the front bolster N, and cables A passed over said pulleys and having their front ends secured

to the purchase-tongue F and their rear ends crossed and secured to the rear runner R, substantially as described.

DUNCAN HALSTEAD.
